Abel L. Brown, Jr.

UNITED STATES PATENT OFFICE.

HARRY J. HAYDEN, JR., OF LAKEWOOD, OHIO, ASSIGNOR TO HARRY J. HAYDEN, SR.,
OF LAKEWOOD, OHIO.

DISPLAY DEVICE FOR USE IN ADVERTISING.

Application filed August 6, 1921. Serial No. 490,321.

To all whom it may concern:

Be it known that I, HARRY J. HAYDEN, Jr., a citizen of the United States, and resident of Lakewood, in the county of Cuyahoga and State of Ohio, have invented certain new and useful Improvements in Display Devices for Use in Advertising, of which the following is a specification.

This invention relates to display devices particularly adapted for use in advertising.

The principal object of the invention is to provide a display device for the general purpose indicated which will in an attractive, effective and attention-compelling manner display the lustrous or mirror-like qualities of certain materials such, for instance, as varnishes or other substances for coating or finishing floors or other surfaces.

The invention consists in the provision of a member having a surface finished with the material which it is desired to display, and an object or figure mounted on or adjacent to the prepared surface in such relation thereto that the figure is reflected in the surface to thereby illustrate the lustrous and glossy character of the material.

Other features of the invention will be hereinafter referred to.

In the drawing, in which a preferred form of the invention has been selected for illustration,

Figure 1 is a view in perspective of a device embodying a preferred form of the invention.

Figure 2 is a side elevation of the device shown in Figure 1 and showing a folded dotted line position of a movable part thereof.

Figure 3 is a plan view of the device in its folded position.

Referring to the drawing for a more detailed description, any suitable object having a surface adapted for display, such as a panel of wood 5, has its upper flat surface 6 smoothly finished and coated with a material, such as varnish, whose merits it is desired to exhibit.

It will be seen that the smooth finish of the panel 5 combined with the transparent and glossy character of the coating layer of varnish 6 produces a reflecting surface of which advantage is taken in the following manner. A figure 7 simulating any desired object and forming an advertising device

designed to attract the attention of an observer is represented in cardboard or other relatively rigid sheet material and mounted near one end of the panel 5 as is indicated in the drawing. Preferably an extension 8 on the sheet bearing the figure is attached by means of a suitable adhesive directly to the upper face of the panel 5 near one end thereof. The unattached portion 7 of the sheet can then be bent or folded along the dotted line 9 in Figure 3 to bring the figure 7 into an upright or angular relation to the flat surface 6 so that when the panel is observed with proper relation to a source of light, the figure 7 will be clearly reflected as at 10 in the varnish surface 6 of the panel 5 itself.

For the best results the figure 7 should face in the general direction from which the light comes and excellent results are obtained when the device is placed in a shop window where it is illuminated by the light entering the window from behind the observer outside the glass. It will be obvious that other situations in which the device can be successfully employed will suggest themselves and that different angular relations between the figure 7 and the surface 6 as well as between the surface 6 and the eyes of the observer can be made use of to correspond to varied lighting and other conditions.

It will be seen that the folding of the figure 7 along the dotted line 9 permits the placing of the figure in a flat non-operative condition for shipment or storage in which, as is indicated in Figures 2 and 3 of the drawing, the figure 7 has been swung forwardly and downwardly into face to face contact with the surface 6 of the panel. The device can thus be mailed or otherwise handled in a flat condition, the figure 7 being bent upward to a suitable angle for exhibition purposes.

I find in practice that excellent results are obtained if the line 9 along which the figure is folded runs at an angle other than a right angle or inclined somewhat to the axis of the panel. I find that the relation of parts thereby attained improves the effect of the reflected figure 10 and makes a pleasing and attractive display. In the display figure illustrated a young girl is pictured in the act of observing her reflection

in the glossy surface. As part of the figure a container 11 for the product from which the mirror-like surface 6 was formed may appropriately be pictured. It will be seen that the device forms an exceedingly effective display device for the purpose described.

What I claim is:

1. A display device for exhibiting a surface coating material comprising: a base member having a surface coated with the material, and a display advertising object attached to said base member in such relation to the coated surface that a reflection of the object is displayed in the surface coating.

2. A display device for exhibiting a surface coating material comprising: a base member having a surface coated with the material, and a display advertising object attached to said base member in variable relation thereto, said object being adjustable to an angular position with relation

to the surface to produce a reflection of the object in the coated surface.

3. A display device for exhibiting a surface-coating material comprising: a base member having a surface coated with the material, an object formed of relatively rigid sheet material mounted on said base member, said object being adapted to be folded into engagement with said surface or to be raised to an angular position in relation thereto to thereby produce a reflection of the object in the surface.

4. A display device for exhibiting a surface-coating material comprising: a base member having a surface coated with the material, and an object mounted on said surface and having a hinged relation thereto whereby said object may be folded into non-operative engagement with said surface or turned to an angular relation to the surface such that a reflected image of the object will appear in said surface coating.

HARRY J. HAYDEN, JR.
